Application December 14, 1953, Serial No. 398,020

13 Claims. (Cl. 260—537)

This invention relates to a process of making organic acids from fatty acids, particularly fatty acids of 14 to 18 carbon atoms. More particularly it relates to the oxidation of fatty acids with nitric acid to produce mono-basic and dibasic acids of lower molecular weight. This application is a continuation in part of our application Ser. No. 318,252, filed November 1, 1952.

One object of the invention is to effect oxidation and splitting of saturated fatty acids such as palmitic and stearic acids, with formation of aliphatic, mono- and di-basic acids of lower molecular weight, the monobasic acids, ranging mainly from 2 to 10 carbon atoms and the di-basic acids from 2-14 carbon atoms, mostly from 6-10 carbon atoms. Other objects of the invention are to increase the yield of useful products, reduce the formation of CO_2 and reduce the consumption of nitric acid employed in the process.

The invention is illustrated by a drawing which shows diagrammatically a plant suitable for carrying out the process.

Various oxidizing agents have been employed heretofore for oxidizing fatty acids to acids of lower molecular weight, including chromic acid, permanganates, nitric acid and air, usually with a catalyst. Because of the stability of the fatty acids, severe oxidizing conditions have been required. For example, it has been the practice to use concentrated or fuming nitric acid, resulting in high acid consumption and production of CO_2 and NO gases. In order to facilitate the oxidation, it has been the practice to employ unsaturated fatty acids or hydroxy acids such as hydroxy stearic or ricinoleic acids which are relatively easily attacked by the oxidizing agent. It has not been considered feasible to oxidize saturated fatty acids because of their high resistance to oxidation, even when employing powerful oxidizing agents such as chromic or concentrated nitric acids. In the presence of these strong oxidizing agents, the initial products of the reaction have been oxidized further to simple compounds of little value such as acetic acid or almost no value such as CO_2 and CO .

We have now discovered that saturated fatty acids, particularly palmitic and stearic acids, can be oxidized to valuable acids of lower molecular weight, both mono-basic and di-basic, by the action of diluted nitric acid at elevated temperature and pressure. We prefer to use acid of about 10 to 30% concentration, 15-20% being very satisfactory, and higher concentrations up to 50% can be employed with close temperature control. The reaction is rapid with good agitation to effect contact between the fatty acid and aqueous nitric acid phases, and no catalyst is required.

It is desirable to operate at a temperature approximating the boiling point of the nitric acid employed, under the pressure selected. Thus at about 100 p. s. i. g. using 20% HNO_3 a temperature of 170° C. was satisfactory. In general, the temperature should be between about 100 and 250° C. depending on the acid concentration and the extent of oxidation desired. Higher temperatures e. g.: 180-250° C. are desired, when employing more dilute acid and/or when converting largely to dibasic acids.

The reaction can be conducted at the vapor pressure of the reaction mixture, and we may also employ a greater pressure by introducing a gas such as air, nitrogen, NO_2 or carbon dioxide. Pressures in the range of about 100

2

to 200 p. s. i. g. are sufficient for most purposes, and we can use pressures in the range of about 50 to 500 p. s. i. g. When conducting the reaction in an autoclave provided with an agitator, the fatty acid and nitric acid are charged, then the vessel is closed and the temperature raised to the desired point. The pressure developed from the expanding vapors of water and acids together with the gases evolved in the reaction, such as CO_2 , N_2 and NO , may be held at any desired point by venting thru a pressure control valve. Internally cooling the vapors serves to condense the water and acids so that only the fixed gases are removed from the autoclave. Fixed gases can also be charged to the autoclave at the start before heating to provide an initial pressure and assist in controlling the reaction.

Referring to the drawing, fatty acid, e. g. stearic, palmitic, oleic acid, or mixed acids from animal, vegetable or marine fats, is charged by line 10 to reaction vessel 11 where it is brought into intimate contact with nitric acid introduced by line 12. Efficient agitation is provided by agitator 13 which can be a multibladed propeller or other suitable type of agitator effective in dispersing the nitric acid and the fatty acid, producing extensive surface and high reaction rate. Coil 14 serves to control the temperature by heating or cooling as needed, suitably by heating with steam or hot water, or cooling with water, cold brine or other refrigerant. After the reaction has been brought to the desired temperature, e. g. 250-300° F., it is generally necessary to supply refrigeration to carry away the exothermic heat of oxidation.

The time of residence of fatty acid in reactor 11 is preferably about ten seconds to five minutes depending on the rate of agitation, temperature and acid concentration each of which speeds the oxidation when increased. Owing to the high agitation and extensive surface between the aqueous phase and the fatty acid phase, the latter is largely oxidized to lower molecular weight organic acids by a process of chain splitting resulting in the formation of monobasic and dibasic acids as the principal reaction product. Gaseous by-products of the reaction are nitrogen, carbon monoxide, carbon dioxide, and nitric oxide, NO . The entire reaction product is continuously removed by line 15 leading to stripper 16 where the gases and the more volatile monobasic acids are removed by vapor line 17 along with steam and nitric acid.

We have found it advantageous to use nitric acid of about 10-30% concentration in water at a pressure of about 3 to 10 atmospheres. Somewhat higher concentrations of acid can be used, e. g. 40-50%, but offer no advantage in yield or conversion, and the use of more concentrated acid increases the cost of the operation, particularly in acid recovery and acid losses. Use of more concentrated acid, above about 30%, increases the corrosion problem with materials for apparatus construction. The mol ratio of nitric acid to fatty acid charged is usually in the range of 4:1 to 30:1, preferably about 10 or 12 to 1.

The pressure is controlled by valve 18 which can be adjusted to hold any pressure desired on reactor 11. We may also extend the reaction time by diverting the products from reactor 11 by valved line 19 to separator 20 where the admixed gaseous by-products are withdrawn with some vapors of nitric acid, water and monobasic acids, the vapors passing by line 21 to cooler 22, thence to receiver 23 where condensate is collected and cool gases are discharged by line 24. Pressure is preferably reduced by valve 25 from the reaction pressure to substantially atmospheric, e. g. 5 to 10 p. s. i. g.

Separator 20 can be provided with a mechanical agitator, or the stream of reaction products can be made to pass over baffles or thru a packing, e. g. stoneware saddles

or rings, to prevent separation of phases and extend the time of reaction of the fatty acid by the hot nitric acid for example from 5 to 30 minutes. From 20, the products flow thru valve 26 and line 15 to stripper 16, valve 27 being closed when operating with separator 20. The volume of separator 20 may equal or exceed the volume of reactor 11 by 2 to 20 fold.

Steam can be introduced by line 28 to the base of stripper 16 to remove more of the volatile acids from the reaction products, mainly monobasic acids ranging from acetic to pelargonic acid or higher. Valeric, caproic, oenanthyllic and caprylic acids are also formed from saturated fatty acids and steam distilled from the dibasic acids in stripper 16. The vapors in line 17 are condensed in condenser 29 and the condensate flows to receiver 23 where uncondensed gases pass out at 24. The water soluble acids form a layer which collects on the surface. Acids from this layer are drawn off continuously or intermittently at 31 and may be redistilled by means not shown.

The soluble, volatile acids, principally propionic and butyric acids, withdrawn by line 30 are recovered for example by extraction, from the dilute nitric acid in which they are dissolved, and the latter is recycled to the reaction chamber 11 by means not shown.

Returning now to stripper 16, the stripped products from the bottom pass by line 32 to trap 33 where unreacted fatty acids and other insoluble, relatively non-volatile acids are withdrawn as an upper layer at line 34. These acids can be recycled to the reactor 11 directly or after redistillation to recover higher boiling monobasic acids of lower molecular weight than the fatty acids charged to the process.

From the bottom of trap 33 the dibasic acids pass by line 35 to extractor 36. Alternatively they can be chilled in cooler 37 to crystallize part of the dibasic acids which are separated by filter 38, whence the filtrate is passed to extractor 36 by line 35.

In extractor 36, the descending stream of dibasic organic acids contact a selective solvent which removes them from the dilute nitric acid, the latter passing by line 39 through heater 40 to stripper 41 where solvent vapors are removed, led by line 42 to condenser 43 and returned to solvent storage tank 44. The solvent is then returned to extractor 36 by pump 45 and line 46.

From the base of stripper 41, dilute nitric acid can be withdrawn from the system by line 47 or recycled to reactor 11 by line 48 and pump 49. Before entering reactor 11, the recycled nitric acid can be fortified by introduction of strong nitric acid from line 12, e. g. 70% HNO₃ can be employed for make up acid to regulate the concentration in reactor 11.

Dibasic acids in solution are conducted by line 50 thru heater 51 to evaporator 52 where solvent is recovered from the acids which are crystallized and discharged at 53. Solvent vapors pass by line 54 to condenser 55, thence by line 56 to solvent supply 44. Vacuum evaporation may be used if desired.

One of the better solvents for extracting dibasic acids from dilute nitric acid is methyl isobutyl ketone—MIBK. The following table shows the solubilities of two samples of mixed dibasic acids in this solvent, in water and in nitric acid:

Solubility of dibasic acids in MIBK

Solvent	Solubility, gm. per 100 cc.		Solubility Ratio, MIBK/Aqueous Phase	
	Sample I	Sample II	Sample I	Sample II
MIBK	48	44		
Water	7	6	6.8	7.3
10% HNO ₃	13	12	3.7	3.7
20% HNO ₃	14	13	3.4	3.4

It will be seen that the solubility of dibasic acids increases with the concentration of the nitric acid used. It is therefore advantageous in acid recovery to employ the lower concentration of nitric acid which, according to our invention, can be made to react with the saturated fatty acids.

The following table shows the solubility of azelaic acid in a number of solvents and the ratio of solubility in 20% HNO₃ at 25° C.

Solubility of azelaic acid

Solvent	Solubility, gm./100 cc.	Ratio of Solubility Solvent/20% HNO ₃
2-Ethyl hexanol-1	8.9	7.4
Di-isobutyl carbinol	8.6	7.2
Trimethyl nonanol	7.2	6.0
Ethyl Acetate	4.9	4.1
Methyl isobutyl ketone	4.2	3.5
Methyl n-amyl ketone	3.9	3.3
Ethyl Butyl Ketone	3.3	2.8
Caprylic-Capric Acid Mixture	5.0	4.2
Crude monobasic acid fraction from oleic acid oxidation (neut. eq. = pelargonic acid)	6.2	5.2
20% nitric acid	1.2	—

25 A preferred solvent should have a boiling point sufficiently low to facilitate recovery by distillation and nitric acid should be readily washed out with water. On this basis we have found the following solvents to be satisfactory: Methyl isobutyl ketone; methyl n-amyl ketone; ethyl butyl ketone. Other solvents suitable for recovery of the dibasic acid are oxygenated, chlorinated or aromatic hydrocarbons. Certain nitrogen or sulfur containing solvents can also be used. 2-ethyl-hexanol and similar high boiling alcohols can be used satisfactorily if the dissolved acids are extracted from them with a suitable base, such as sodium hydroxide, ammonium hydroxide, etc.

30 We can use monobasic acids produced in the process to extract the dibasic acid product and for this purpose we prefer to use a fraction of selected volatility to aid separation from the relatively non-volatile dibasic acids. Thus a water insoluble fraction of mixed monobasic acids having about six to nine carbon atoms is quite suitable. When using these monobasic acids as solvents, it is not necessary to recover them from the nitric acid 35 which is recycled to the reactor 11, inasmuch as the monobasic acids recycled to the reactor are converted therein to valuable dibasic acids.

40 Following is the composition of a mixture of dibasic acids which we obtained from the oxidation of palmitic acid in an autoclave. Six-tenths mol of palmitic acid (90% pure) was heated and agitated 30 minutes with 2266 cc. of nitric acid—20%, at 170° C. The pressure was adjusted with nitrogen to 100 p. s. i. g. before heating, and held there during the reaction. Fifty percent of the palmitic acid was converted, the yield of dibasic acids (calculated as azelaic) being 99% of the acid converted.

Composition of dibasic acids from palmitic acid

	Acid	Comp., Mol Percent
65	Succinic, 4 carbons	6.9
	Glutaric, 5 carbons	5.5
65	Adipic, 6 carbons	11.7
	Palmitic, 7 carbons	18.5
65	Siberic, 8 carbons	23.8
	Azelaic, 9 carbons	8.6
65	Sebacic, 10 carbons	8.5
	Undecanedioic, 11 carbons	4.1
65	Dodecanedioic, 12 carbons	3.9
	Tridecanedioic, 13 carbons	4.0
70	Tetradecanedioic, 14 carbons	4.5

75 The unconverted palmitic acid from the above was found to contain 5.4% nitrogen which was found to be mostly in nitroso derivatives; about 10% being in nitro

derivatives, apparently intermediate reaction products. A portion of the mixed dibasic acids was esterified with butyl alcohol, giving the dibutyl ester, a valuable plasticizer for plastics, and resins.

Another autoclave oxidation of palmitic acid was run as before but the charge (153.6 gms.) was pressured with CO_2 to 50 p. s. i. g. before heating. Analysis of the products was made in the following manner: one-half was worked up for monobasic and dibasic acids and unreacted palmitic acid. The other half was used to determine nitric acid balance. Nitrogen in the organic material was determined by the Dumas method. Unused HNO_3 was determined by titration, correcting for extractable organic acids. The results are given in the following table:

Products from palmitic acid oxidation

Product	Weight (Grams)	Percent
Unreacted palmitic acid.....	59.1	38.5
Monobasic acids (calculated as $\text{R}-\text{CH}_2$).....	10.5	6.8
Dibasic Acids (Calculated as $\text{CH}_2-\text{R}-\text{CO}_2\text{H}$).....	53.7	35.0
CO_2 and CO (Calculated as CH_2).....	18.4	12.0
Not accounted for.....	11.9	7.7

Nitric acid balance

Form	HNO_3 Equivalents
Nitrogen.....	1.18
Nitric Oxide (NO).....	1.94
Residual Acid.....	3.65
Combined Organic.....	0.35
Not accounted for.....	0.20

Of the nitric acid charged, 97% was accounted for.

The foregoing data are typical of the results obtained in batch operation with saturated fatty acids such as myristic, palmitic, stearic and arachidic. The product acids are readily separated from each other by distillation and/or crystallization in a manner well known in the art. For use as plasticizers, the dibasic acids can be converted to their esters, for example the diethyl or dinonyl esters. These esters are also valuable lubricating oils for use in critical service in aviation because of their excellent low temperature and high temperature characteristics. For this purpose, mixtures can be used and are generally preferred.

Altho our process is directed to the oxidation of saturated fatty acids, it is not necessary to use pure, saturated acids as charging stock but mixed acids containing substantial amounts of unsaturated acids can be used and we prefer to use the natural fatty acids derived from beef tallow, sperm oil, coconut oil, horse fat, mutton tallow, palm nut oil, peanut oil, tall oil, and wool fat. The acids derived from these fats, for example by use of the Twitchell acid saponification, generally have iodine values less than about 100 and usually in the range of about 25 to 75. Monobasic acids of higher molecular weight, e. g. 10 to 14 carbon atoms, are usually allowed to remain with the unconverted fatty acid which is recycled to the oxidation reaction.

Having thus described our invention what we claim is:

1. The process of converting saturated fatty acids of 14 to 18 carbon atoms to dibasic acids of lower molecular weight which comprises intimately contacting said fatty acids with an oxidizing agent consisting of dilute nitric acid at a temperature of 100 to 250° C. and a pressure in the range of about 50 to 500 p. s. i. gage, the mol ratio of nitric acid to fatty acid charged being within the range of about 4:1 to 30:1 and separating from the unconverted fatty acid, dibasic organic acids of lower molecular weight.

2. The process of claim 1 wherein the nitric acid concentration is about 10 to 30% HNO_3 .

3. The process of claim 1 wherein volatile monobasic acids are separated from the reaction products by distillation and the nitric acid is recycled to the conversion step of the process.

4. The process of converting saturated fatty acids of 14 to 18 carbon atoms into dibasic organic acids of lower molecular weight which comprises continuously charging said fatty acid and an oxidizing agent consisting of nitric acid to a reaction zone, maintaining the concentration of nitric acid in said reaction zone at about 5 to 30 percent with respect to the water present, maintaining the mol ratio of nitric acid to said fatty acid charged within the range of about 4:1 to 30:1, vigorously agitating the contents of said reaction zone to provide intimate contact between the three phases therein, oil, aqueous and gaseous, maintaining a pressure on said reaction zone between about 50 and 500 p. s. i. gage, controlling the temperature of said reaction zone within the range of about 100-250° C., continuously withdrawing reaction product from said reaction zone, reducing the pressure in a distillation zone and distilling volatile organic acids therefrom, and thereafter separating water soluble, relatively nonvolatile dibasic acids from unreacted fatty acids.

5. The process of claim 4 wherein said unreacted fatty acids are recycled to said reaction zone.

6. The process of claim 4 wherein nitric acid is recovered from said dibasic acids by extraction with a selective solvent and recycled to said reaction zone.

7. The process of claim 4 wherein the temperature of said reaction zone is about 135 to 200° C.

8. The process of claim 5 wherein the lower molecular weight monobasic acids remaining with said unreacted fatty acids are distilled therefrom before said fatty acids are recycled to said reaction zone.

9. The process of converting fatty acids of 14 to 18 carbon atoms to dibasic acids with a lesser number of carbon atoms which comprises continuously charging said fatty acid to a reaction zone and agitating it therein with an oxidizing agent consisting of nitric acid of about ten to fifty percent concentration, maintaining the mol ratio of nitric acid to fatty acid charged to said reaction zone within the range of about 4:1 to 30:1, maintaining the temperature of said reaction zone at a point within the range of about 150 to 250° C., maintaining the pressure of said reaction zone at least at the vapor pressure of the nitric acid therein, continuously removing reaction products from said reaction zone without separation and expanding them into a vaporizing zone at lower pressure, recovering volatile products from said vaporizing zone and recovering dibasic acids from the non-volatile fraction withdrawn from said vaporizing zone.

10. The process of claim 9 wherein said fatty acids to be converted have an iodine value in the range of 25 to 75.

11. The process of claim 9 wherein the non-volatile products from said vaporizing zone are separated into an insoluble layer comprised of unreacted fatty acids and an aqueous layer containing dibasic acids, and the unreacted fatty acids are recycled to the reaction zone.

12. The process of claim 11 wherein the dibasic acids are recovered from the aqueous layer by solvent extraction.

13. The process of claim 12 wherein the solvent used in said extraction is selected from the class consisting of methyl isobutyl ketone, methyl n-amyl ketone and ethyl butyl ketone.
